UNITED STATES PATENT OFFICE.

BENJAMIN G. LAMME, OF PITTSBURG, AND CHARLES E. SKINNER, OF WILKINSBURG, PENNSYLVANIA, ASSIGNEES TO THE WESTINGHOUSE ELECTRIC AND MANUFACTURING COMPANY, OF PENNSYLVANIA.

FIELD-MAGNET COIL FOR ELECTRICAL MACHINES.

SPECIFICATION forming part of Letters Patent No. 633,858, dated September 26, 1899.

Application filed June 14, 1899. Serial No. 720,524. (No model.)

To all whom it may concern:

Be it known that we, BENJAMIN G. LAMME, residing at Pittsburg, and CHARLES E. SKINNER, residing at Wilkinsburg, in the county 5 of Allegheny and State of Pennsylvania, citizens of the United States, have invented a new and useful Improvement in Field-Magnet Coils for Electrical Machines, (Case No. 840,) of which the following is a specification.

10 Our invention relates to dynamo-electric machines, and particularly to field-magnet coils for such machines.

The object of our invention is to provide a field-magnet coil which shall be thoroughly 15 and effectively ventilated and insulated in such manner that coils of large cross-section may be utilized without any substantial increase in copper loss.

In the construction of electrical machines, 20 particularly alternating-current electric generators for a relatively low rate of alternations, it is often desirable to have a comparatively small number of poles and to make the machines of as small dimensions as is consistent with the output desired. In order to attain these results, it is necessary to provide 25 a small number of field-magnet coils which are individually of large cross-section, and in order to keep down the copper loss within 30 reasonable limits we propose to form each coil of a plurality of concentric sections or divisions separated from each other by air-spaces and where the conditions will permit to insulate the several turns of each section by interposed strips or plates of material, leaving 35 the edges of the turns bare, so as to dissipate the heat therefrom into the atmosphere.

In the accompanying drawings, Figure 1 is a face view of a coil constructed in accordance with our invention, portions being broken away and in section. Fig. 2 is a sectional view of a portion of a field-magnet frame, pole-piece, and field-magnet coil, the portion of the frame and coil being shown in 45 section. Fig. 3 is a detail view of one of the sections or divisions shown in Fig. 1. Fig. 4 is an outline view, partially diagrammatic in character, of a field-magnet provided with a set of coils like that shown in the preceding 50 figures.

The details of construction, as illustrated in the drawings, are as follows:

The field-magnet frame 1 may be either stationary or rotatable, and if the latter may rotate on either a vertical or a horizontal axis. 55 The pole-pieces 2 may be either cast in or bolted to the frame 1. In the particular form shown the pole-pieces are bolted to the frame. Each of the field-magnet coils 3 comprises four concentric sections or divisions 4; but the 60 number of such divisions may be greater or less than that shown, depending upon the size of the machine, the number of poles, and the amount of copper desired in any particular case. Each section 4 consists of a number of 65 turns of copper strap 5, the strap being bent edgewise into the form desired and into as many turns as will provide the magnetizing effect required. Between each two adjacent turns 5 we place one or more strips or plates 70 6 of suitable insulating material, the most desirable material for this purpose being composed of mica and shellac formed into a compact mass or body of the requisite thickness. We do not limit ourselves, however, to any 75 particular insulating material for use in this connection.

The concentric divisions or sections 4 are separated from each other by air-spaces 7 of the desired dimensions, and the sections are 80 spaced apart and retained in proper relative position by means of bars 8, extending substantially perpendicularly to the face of the coil and provided with insulating coverings 9. The number of these bars or rods may be varied 85 within considerable limits, as will be readily understood.

In order to provide sufficient insulation between the edges of the sections of the coil and the casing at the two sides or faces, we provide a few outer turns of less width, three of such turns in each set and on each side of the coil being shown in Figs. 2 and 3 of the drawings. The number of narrow turns required will depend upon the thickness of strap 95 used and the amount of insulation required. Over these narrow turns are fitted insulating-caps 10, constructed of mica and shellac or other suitable material.

The entire coil, built up as described, is 100

placed in a suitable casing 11, provided with 5 ventilating-openings 12, so located with reference to the spaces 7 between the divisions of the coil as to permit free circulation of air, the several parts of the casing being bolted or riveted together in order to securely retain the coil in position.

The spacing-bars 8 may be fastened in position by means of screws or pins passing 10 through the face-plate of the casing, as indicated in the drawings. The incased coil may be supported upon the field-magnet frame and pole-pieces in any suitable manner. As 15 shown in the drawings, the coil is securely held between the enlarged inner end 2^a of the pole-piece and a supporting skeleton or open-work frame 13, resting at one side against the inner periphery of the frame 1 and at its other side against the inner face of the coil-casing 11.

By reason of the air-spaces between the coil-sections, the corresponding openings in the casing, and the open-work structure of the frame 13 currents of air circulate freely 25 through and around the coil and serve to keep the temperature within safe limits. The air-circulation is especially effective in machines of the rotary field-magnet type.

While a specific coil structure adapted to 30 a certain type of machine is shown and described, we desire it to be understood that the form and dimensions of the coil and the several parts composing it may be varied within considerable limits from what is shown 35 without departing from the invention, the essential features of which are the subdivision of the coil into two or more substantially concentric divisions or sections and the provision of air-spaces between said sections.

40 We claim as our invention—

1. A field-magnet coil for electrical machines comprising a plurality of concentric divisions of copper strap bent edgewise, the turns of each division being separated by insulation and the several divisions having bare 45 edges separated by air-spaces.

2. A field-magnet coil for electrical machines comprising a plurality of sections built up of alternate turns of bare copper strap and sheet-mica and insulated spacing bars or 50 rods interposed at intervals between adjacent sections.

3. A field-magnet coil for electrical machines comprising a plurality of concentric sections severally built up of bare strap-copper 55 and sheet or strap insulation, said sections being spaced apart by insulated bars extending at right angles to the plane of the coil.

4. A field-magnet coil for electrical machines comprising a plurality of concentric sections of bare strap-copper the turns of which are superposed and separated by insulation, the divisions being separated by air-spaces. 60

5. A field-magnet coil for electrical machines, comprising a plurality of concentric sections of coiled copper strap the turns of which are separated by sheet-mica, insulated bars for spacing apart the coil divisions and 70 an open-work frame for receiving and supporting the coil.

In testimony whereof we have hereunto subscribed our names this 13th day of June, 1899.

BENJ. G. LAMME.
C. E. SKINNER.
